CLAIM

I claim the ornamental design for the surgical jaws, as shown and described.

DESCRIPTION

FIGS. 1 and 3 present top perspective views of the ornamental surgical jaws of the present invention. FIG. 1 depicts the surgical jaws in a closed configuration whereas FIG. 3 depicts the same surgical jaws in an open configuration. FIGS. 2 and 4 present bottom perspective views of the ornamental surgical jaws depicted in FIGS. 1 and 3, respectively. FIG. 2 depicts the surgical jaws in a closed configuration whereas FIG. 4 depicts the same surgical jaws in an open configuration.

FIGS. 5 and 7 present left side elevational views of the ornamental surgical jaws depicted in FIGS. 1 and 3, respectively. FIG. 5 depicts the surgical jaws in a closed configuration whereas FIG. 7 depicts the same surgical jaws in an open configuration.

FIGS. 6 and 8 present right side elevational views of the ornamental surgical jaws depicted in FIGS. 1 and 3, respectively. FIG. 6 depicts the surgical jaws in a closed configuration whereas FIG. 8 depicts the same surgical jaws in an open configuration.

FIG. 9 presents a top down plan view of the ornamental surgical jaws depicted in FIG. 1.

FIG. 10 presents a bottom up plan view of the ornamental surgical jaws depicted in FIG. 1.

FIG. 11 presents a front elevational view of the ornamental surgical jaws depicted in FIG. 1.

FIG. 12 presents a rear elevational view of the ornamental surgical jaws depicted in FIG. 1.

FIGS. 13 and 15 present close-up, top perspective views of the ornamental surgical jaws depicted in FIGS. 1 and 3, respectively. FIG. 13 depicts the surgical jaws in a closed configuration whereas FIG. 15 depicts the same surgical jaws in an open configuration.

FIGS. 14 and 16 present bottom perspective views of the ornamental surgical jaws depicted in FIGS. 13 and 15, respectively. FIG. 14 depicts the surgical jaws in a closed configuration whereas FIG. 16 depicts the same surgical jaws in an open configuration.

FIGS. 17 and 19 present left side elevational views of the ornamental surgical jaws depicted in FIGS. 13 and 15, respectively. FIG. 17 depicts the surgical jaws in a closed configuration whereas FIG. 19 depicts the same surgical jaws in an open configuration.

(Continued)

FIGS. 18 and 20 present right side elevational views of the ornamental surgical jaws depicted in FIGS. 13 and 15, respectively. FIG. 18 depicts the surgical jaws in a closed configuration whereas FIG. 20 depicts the same surgical jaws in an open configuration.

FIG. 21 presents a top down plan view of the ornamental surgical jaws depicted in FIG. 13 (closed configuration). FIG. 22 presents a bottom up down plan view of the ornamental surgical jaws depicted in FIG. 13 (closed configuration); and,

FIG. 23 presents a front elevational view of the ornamental surgical jaws depicted in FIG. 13 (closed configuration). The broken lines shown in FIGS. 1 to 23 depict portions of the surgical jaws that form no part of the claim.

1 Claim, 10 Drawing Sheets
